Primary Examiner — Mark Goodwin*(74) Attorney, Agent, or Firm* — Wood, Herron & Evans, LLP(57) **CLAIM**

The ornamental design for medication packaging assembly, as shown and described.

DESCRIPTION

FIG. 1 is a top perspective view of a first embodiment of a medication packaging assembly showing the body portion of my new design;

FIG. 2 is a bottom perspective view thereof;

FIG. 3 is a top plan view thereof;

FIG. 4 is a cross-sectional view thereof taken along line 4-4 of FIG. 3;

FIG. 5 is a front view thereof;

FIG. 6 is a right side view thereof;

FIG. 7 is a rear view thereof;

FIG. 8 is a left side view thereof;

FIG. 9 is a bottom plan view thereof;

FIG. 10 is a top perspective view of a second embodiment of a medication packaging assembly showing my new design in assembled condition;

FIG. 11 is a bottom perspective view thereof;

FIG. 12 is a top plan view thereof;

FIG. 13 is a cross-sectional view thereof taken along line 13-13 of FIG. 12;

FIG. 14 is a front view thereof;

FIG. 15 is a right side view thereof;

FIG. 16 is a rear view thereof;

FIG. 17 is a left side view thereof; and,

FIG. 18 is a bottom plan view thereof.

The broken line showing of various surface features is included for the purpose of illustrating portions of the medication packaging assembly and forms no part of the claimed design.
